HENRY H. GOVE, OF BIDDEFORD, MAINE, ASSIGNOR OF ONE-HALF TO HOWARD R. WHITEHEAD, OF SACO, MAINE.

LOOM-SHUTTLE.

1,363,584.

Specification of Letters Patent. Patented Dec. 28, 1920.

Application filed February 23, 1918. Serial No. 218,615.

To all whom it may concern:

Be it known that I, HENRY H. GOVE, a citizen of the United States, residing at Biddeford, in the county of York and State 5 of Maine, have invented certain Improvements in Loom-Shuttles, of which the following description, in connection with the accompanying drawings, is a specification, like reference characters on the drawings 10 indicating like parts in the several figures.

This invention relates to loom-shuttles of the type designed particularly for use in automatic weft-replenishing or feeler looms. Looms of this type are widely used commercially and they comprise a feeler mechanism which operates when the filling on the bobbin or other weft carrier (hereinafter referred to as a bobbin) is nearly exhausted to throw into operation a mechanism that 20 forces a full bobbin into the shuttle, this new bobbin acting to crowd the nearly empty one out of the shuttle. It is then necessary to sever the weft or filling between the ejected bobbin and the goods. Usually this weft is 25 cut at two points, one close to the selvage and the other adjacent to the shuttle. It is preferable, however, for many reasons to sever this weft in the shuttle. While it has been proposed heretofore to equip shuttles 30 with cutting mechanism designed to accomplish this object, these constructions have never proved successful commercially, so far as I have been able to learn, and accordingly it is at the present time the universal 35 practice, so far as I am aware, to sever the filling at points outside of the shuttle.

The present invention aims to devise a simple, reliable and thoroughly practical cutting mechanism for a loom-shuttle. The 40 manner in which it is proposed to accomplish this object will be readily understood from the following description and the novel features will be particularly pointed out in the appended claims.

Referring now to the accompanying drawings:

Figure 1 is a plan view of a shuttle equipped with a weft cutting mechanism embodying the present invention;

50 Fig. 2 is a front elevation of the cutting mechanism shown in Fig. 1 when removed from the shuttle.

Fig. 3 is a vertical, cross sectional view substantially on the line 3—3, Fig. 2;

55 Fig. 4 is a transverse cross-sectional view,

through the shuttle box, of a loom showing the shuttle therein and showing certain parts of the weft-replenishing mechanism;

Fig. 5 is a skeleton view, partly in cross section, showing the opposite side of the cutting device from that shown in Fig. 2; and

Fig. 6 is a longitudinal cross sectional view through the shuttle box and certain parts adjacent thereto.

In the drawings, 2 indicates a shuttle 65 body provided with a longitudinal opening 3 extending therethrough from top to bottom and through which the bobbin 4 is inserted and ejected. At one end of the opening 3 spring jaws 5 are provided to grip the 70 base 6 of the bobbin and the opposite end of the shuttle is equipped with a threading device 7 of the type commonly used in shuttles of this character. All of these parts are of the usual construction.

75 The cutting mechanism provided by this invention is mounted in the opening 3 at a point between the tip of the bobbin and the threading device 7. This mechanism comprises a plate 8 that may be set into grooves 80 formed in the walls of the opening 3 and secured in position by screws passing through the sides of the shuttle and entering holes 9 drilled in the opposite edges of the plate. A thread guiding hole 10 is formed in the 85 plate 8 so that it aligns with the thread guiding aperture in the member 7. The thread cutting members *per se* consist of two blades 11 and 12, respectively, both mounted on a headed stud 14 positioned below the 90 thread guiding opening 10. These blades constitute a pair of shears and they have co-operating cutting edges that straddle the path of travel of the thread as it is unwound from the bobbin and runs through the thread 95 guides 7 and 10. In order to prevent the stud 14 from turning, it is provided with a squared end 15 which enters a correspondingly shaped socket formed in the front of the plate 8 and it is held in this socket by 100 a screw 16.

Each of the blades 11 and 12 consists of a bell crank lever, the blade 11 being provided with the arm 17 and blade 12 with the arm 18. A link 19 connects the arm 17 with an 105 arm 20 pinned to a rock shaft 21 that projects through the plate 8 and turns freely in bearings rigid with the plate. A similar link 22 connects the arm 18 of the blade 12 with an arm 23 pinned to a rock shaft 24 110

that projects through the plate 8 parallel to the rock shaft 21. At the opposite side of the plate from the shears the rock shafts 21 and 24 are shaped to form arms that are 5 bent toward each other, as clearly shown in Figs. 1 and 2, and these arms have wings 25 and 26, respectively, fixed to them. When these wings are depressed by pressure exerted on their adjacent edges they operate 10 through the connections just described to swing the blades 11 and 12 together, thus causing them to sever the thread which they straddle. As soon as the actuating pressure on the wings is relieved, the blades 11 and 12 15 are immediately opened again by springs 27 and 28, respectively, the spring 27 being connected at its upper end to a lug on the plate 8 and at its lower end to a lug projecting from the link 22, and the other spring 28 20 being correspondingly connected to the link 19. The range of movement of these blades under the influence of the springs 27 and 28 is limited by stops 29 and 30, arranged to engage shoulders formed, respectively, on 25 the links 22 and 19.

Referring now to Figs. 4 and 6, it will be seen that the shuttle 2 is there shown in the shuttle box 32 and that the hammer 33 and fork 33' of the bobbin-changing mechanism 30 is about to force a new bobbin 34 from the holder or hopper 35 into the shuttle located in box 32. As above stated, the act of forcing the full bobbin into the proper position in the shuttle ejects the empty bobbin from 35 the shuttle. As the tip of the full bobbin 34 is forced down into its proper position in the shuttle, it depresses the wings 25 and 26 as it passes down between them and thus operates the shears 11 and 12 causing them to cut 40 the filling thread that extends from the outgoing bobbin to the selvage of the cloth. Fig. 5 shows the shears at the instant that the bobbin tip 4 is about to pass down out of engagement with the wings and in the 45 positions that they occupy just after completing the cutting operation.

This mechanism, therefore, cuts the filling thread close to the bobbin so that as the substantially empty bobbin is ejected, the thread 50 end that trails behind it is so short that there is absolutely no danger of its catching in any part of the shuttle. This bobbin, therefore, drops freely out of the machine carrying the trailing end of the filling thread 55 with it. As soon as the tip of the full bobbin has passed below the wings 25 and 26 the springs 27 and 28 will return the blades 11 and 12 to their open positions. While the shears might be operated by the out-going or 60 ejected bobbin, an important feature of this invention is the arrangement whereby they are operated by the incoming bobbin. It will be seen from an inspection of Fig. 6 that when the hammer 33 and fork 33' move 65 downwardly to force the full bobbin 34 into

the shuttle, thus displacing the empty bobbin 4, the base 6 of the empty bobbin may be forced out of the jaws 5 so quickly that the tip of this bobbin will not be pushed against the wings with sufficient force to insure the 70 proper operation of the shears. This is particularly likely to happen if the new bobbin happens to be a short one, that is, is only partially filled. The base of the bobbin, being larger than the tip, is engaged by the 75 base of the incoming bobbin before the filling on the incoming bobbin engages the bobbin spindle. Consequently, the base is shot out of the shuttle with considerable force and its tip swings toward the base and either 80 moves entirely clear of the wings, or engages them so lightly that it does not operate them. Any danger of failure due to this cause is eliminated by the construction herein shown and described, since the transerrer 85 that forces the full bobbin into the shuttle positively moves the tip as well as the base of the bobbin. There is, therefore, no opportunity for the tip of the bobbin to dodge the wings of the cutting mechanism. It is 90 impossible for the transferring operation to be completed without actuating the cutting mechanism. This mechanism might also be operated by some part of the transerrer, but I prefer the arrangement shown, particularly since the movement transmitted by the transerrer to the incoming bobbin is substantially as positive as is the movement of the transerrer itself. 95

The converging construction of the wings 100 and the fact that they are inclined toward each other, as shown in Figs. 3 and 4, tends to center the bobbin tip between them and insure the operation of both the blades 11 and 12. As a further provision for insuring the 105 complete cutting of the filling thread I have mounted the blades 11 and 12 on the stud 14 so that they can not only pivot on this stud, but can also have a relative sliding movement longitudinally of the stud and I have 110 sprung or inclined the points of the blades laterally toward each other. A spring 36, Fig. 3, presses the blade 11 toward the blade 12 so that as the blades 11 and 12 are closed to perform their cutting operation, their cutting edges are constantly pressed together at their point of intersection as this point travels outwardly along the edges of the blades toward their tips. This construction 115 insures the complete severance of the thread 120 at each cutting operation, even after the parts have become considerably worn and it tends to prevent the wear of the blades from dulling them. These features thus contribute to the life and the reliability of the 125 mechanism. It will be noted that the construction shown avoids the use of delicate parts which might easily become broken and that it provides a very sturdy and substantial construction capable of operating for a 130

long period without attention or repair. An advantage of the wings 25 and 26, in addition to that above mentioned, is that they facilitate the shuttle threading operation 5 and that their peculiar shape makes it impossible for the thread to catch on them as it balloons off the end of the bobbin tip during the weaving operation.

What is claimed as new is:

- 10 1. A shuttle for weft replenishing looms, said shuttle being provided with thread guiding means and having an opening therethrough to receive a bobbin and to permit the ejection of said bobbin, shears comprising two movable blades mounted in said shuttle in position to straddle the thread as it is unwound from said bobbin and travels through said thread guiding means, and actuating means for said shears arranged to 15 be operated by the engagement therewith of a bobbin during the bobbin changing operation.
- 20 2. A shuttle for weft replenishing looms, said shuttle being provided with thread guiding means and having an opening therethrough to receive a bobbin and to permit the ejection of said bobbin, coöperating movable cutters mounted in said shuttle in position to cut the thread adjacent to said thread 25 guiding means, and actuating devices for said cutters arranged to be operated by the contact therewith of an incoming bobbin.
- 30 3. A shuttle for weft replenishing looms, said shuttle having an opening therethrough to receive a bobbin and to permit the ejection therefrom of said bobbin, cutting members mounted in said shuttle for relative movement to enable them to sever the filling thread, and movable devices for 35 operating said members mounted in the path of movement of the tip of the bobbin during the bobbin changing operation and exerting a centering action on the bobbin tip.
- 40 4. A loom-shuttle provided with thread guiding means and having an opening therethrough to receive a bobbin and to permit the ejection of said bobbin, shearing members mounted in said shuttle for relative movement to sever the thread at a point 45 adjacent to said thread guiding means, means acting on said members to hold them constantly in shearing engagement as the point of shearing action travels along them 50 during their relative movement, and actuating means for said members arranged to be engaged by the tip of an incoming bobbin and to be operated thereby.
- 55 5. A loom-shuttle provided with thread guiding means and having an opening therethrough to receive a bobbin and to permit the ejection of said bobbin, a pair of shears comprising two pivoted blades between which the thread passes in traveling through 60 said guiding means, a stud on which said

blades are pivoted and on which they are mounted for relative movement toward and from each other, said blades being inclined toward each other, a spring operative to press said blades together to hold the edges 70 of the blades in shearing contact as the point of shearing action travels outwardly along said edges during the cutting movement of the blades, actuating means for said blades arranged to be operated by the engagement therewith of a bobbin during the bobbin changing operation and spring means connected with said blades to hold them normally open.

6. A thread cutting device for a loom-shuttle comprising a plate provided with a thread receiving opening, a stud mounted adjacent to said opening, a pair of blades pivotally mounted on said stud and constituting shears, spring means operative 75 normally to hold said shears open, arms pivoted in said plate and arranged to be turned on their axes by the passage of a bobbin between them, and connections between said arms and blades for causing the 80 movement of the arms to close the shears.

7. A thread cutting device for a loom-shuttle, comprising a plate provided with an opening for the passage therethrough of a bobbin thread, a stud mounted adjacent 95 to said opening, a pair of blades pivotally mounted on said stud and constituting shears, spring means operative normally to hold said shears open, a pair of arms pivoted on said plate and arranged to be turned 100 on their axes by the engagement therewith of a portion of the bobbin, and links connecting said arms and said blades whereby the movement of the arms operates the shears.

8. A shuttle for weft replenishing looms, said shuttle being provided with thread guiding means and having an opening therethrough to receive a bobbin and to permit the ejection of said bobbin, thread 110 cutting means mounted in said shuttle in position to sever the bobbin thread adjacent to said thread guiding means, and actuating devices for said thread cutting means mounted in the path of movement of the 115 tip of the bobbin during the bobbin changing operation and serving to guide the thread toward said thread guiding means.

9. A shuttle for weft replenishing looms, said shuttle being provided with thread guiding means and having an opening therethrough to receive a bobbin and to permit the ejection of said bobbin, thread 120 cutting means mounted in said shuttle in position to sever the bobbin thread adjacent to said thread guiding means, and actuating devices for said thread cutting means mounted in the path of movement of the tip of the bobbin during the bobbin changing operation and including wings 125 130

diverging from a point adjacent to the thread severing means.

10. A shuttle for weft replenishing looms, said shuttle being provided with thread guiding means and having an opening therethrough to receive a bobbin and to permit the ejection of said bobbin, thread cutting means mounted in said shuttle in position to sever the bobbin thread adjacent to said thread guiding means, and actuating means for said thread cutting means

comprising two pivotally mounted wings between which the tip of a bobbin is forced during the bobbin-changing operation, said wings being downwardly inclined toward each other whereby they tend to center the bobbin tip during its engagement with them and having their free ends flared away from each other.

In testimony whereof I have signed my name to this specification.

HENRY H. GOVE.
